UNITED STATES PATENT OFFICE.

JOSEPH W. COLLINS, OF CLEVELAND, OHIO, ASSIGNOR OF ONE-THIRD TO BARBARA FREDERICK, OF CLEVELAND, OHIO.

SAFETY DEVICE FOR STREET-CARS AT DRAWBRIDGES.

No. 888,588.

Specification of Letters Patent.

Patented May 26, 1908.

Application filed March 3, 1908. Serial No. 419,023.

To all whom it may concern:

Be it known that I, JOSEPH W. COLLINS, a citizen of the United States, residing at Cleveland, in the county of Cuyahoga and State of Ohio, have invented a new and useful Safety Device for Street-Cars at Drawbridges, of which the following is a specification.

My invention relates to improvement in safety device for street cars approaching turning or swing-bridges in which a combination of guards and levers operate in conjunction with the opening and closing of the bridge; and the objects of my improvement are, first, to provide safety guards in direct path of street cars near the draw when draw is open; and, second, to protect cars not under control when approaching the open draw and avoid the danger to the use of an open switch. I attain these objects by the mechanism illustrated in the accompanying drawing, in which the figure is a view in perspective of the guards, levers, and hangers, and sections of the track on and near the drawbridge.

The rails A A' show the approach and B B' adjoining end of draw.

C, D, and E, constitute the supports or hangers and hold the guards and lever in

movable position. In the hanger D rests lever F to one end of which is attached a wheel and weight to overbalance its connections. At end of draw is fastened a circular track I, so constructed that its ends will strike or pass from underneath the lever-wheel, raising or lowering the lever and guards when the drawbridge is turned to open or close; the lever F being connected with the cross-plate made fast to guards G G'.

I claim:

In a device of the character described, guards, the ends of which conform to the surface of the rails, and adapted to project upward into the path of the car, said guards having a weighted lever, and wheel attached, which wheel and end of lever are also adapted to be moved upwards or downwards, in combination with a drawbridge having a circular track made fast to the end of the drawbridge to move said lever upwards or downwards, and to operate the guards incidentally when the draw-bridge is opened or closed, substantially as herein described.

JOSEPH W. COLLINS.
